UNITED STATES PATENT OFFICE.

OLIVER C. SWAN, OF DENVER, COLORADO, ASSIGNEE, BY DIRECT AND MESNE ASSIGNMENTS, TO THE SWAN PROCESS OIL COMPANY, A CORPORATION OF COLORADO.

PROCESS AND APPARATUS FOR TREATING OILS.

1,250,527.

Specification of Letters Patent. Patented Dec. 18, 1917.

Application filed February 21, 1916. Serial No. 79,680.

To all whom it may concern:

Be it known that I, OLIVER C. SWAN, a citizen of the United States, residing in the city and county of Denver and State of Colorado, have invented certain new and useful Improvements in Processes and Apparatus for Treating Oils; and I do hereby declare the following to be a full, clear, and exact description of the invention, such as will enable others skilled in the art to which it appertains to make and use the same.

My invention relates to an improved process and apparatus for treating oils, particularly lubricating and cylinder oils that have been used, for the purpose of reclaiming same by removing the impurities therefrom and restoring the oils to their normal, or even improved conditions, thereby renewing their effectiveness and prolonging indefinitely their possible duration of use.

It is believed to have been demonstrated, and is now understood, that oils do not wear out mechanically; and in tests employing my invention, the specific gravity, and viscosity (the primary lubricating value) of reclaimed oils have even been actually increased, in comparison to that of unused oil of the same brand and grade.

Owing to the enormous loss, that ordinarily results from discarding this refuse oil, various means have been employed for filtering and purifying waste oils, especially in connection with the lubricating systems of large plants and factories.

However this may be, it is singularly true, that almost incredible losses are annually sustained in the waste, by disuse, of the heavy, viscous, cylinder lubricating oils, the refuse from internal combustion or gas engines or motors, whether of the stationary or mobile types, or whether aerial, marine or land motors, wherein it is not feasible to install a refining or purifying system.

While it will be understood that my invention is not limited in its application to any specific use or source of waste oil supply, still for the purpose of simplicity in fully disclosing the invention, in the following specification I will particularly refer to its use in connection with the refuse oil taken from the engines of automobiles, the essential features of novelty of the invention being more succinctly stated in the appended claims.

When a machine is run into a garage for

repairs to the engine or for overhauling, the lubricating oil is drained off and allowed to run to waste.

Also the used lubricating oils, especially from the cylinders and crank base of gasoline engines, besides becoming densely discolored and malodorous, are more or less gummy, and are heavily charged with carbon in suspension and other foreign substances, manifestly detrimental, in that state, for use as a lubricant. In fact, in motor boat and automobile engines, the oil becomes so heavily laden with carbon and impurities that, for the most effective operation, it is desirable to draw off the used oil and replace it by new oil, after the engine has been running for some time, say a period equivalent to a run of from seven hundred to one thousand miles. This drawn off oil is also allowed to run to waste.

With systems heretofore employed for purification purposes, it is believed to be impracticable to entirely eliminate the suspended carbon in used gas engine oils, the suspended matter being substantially of the same specific gravity as the oils, so that, even after successive filtrations, microscopic inspection reveals minute particles of carbon.

By my invention, however, the successful reclamation of the used oil is in part due to the introduction of a suitable harmless treating agent, such as kieselguhr into intimate commingled relation with the oil being reclaimed, for preparing the same *en masse* for more effective filtration.

In specifically disclosing the invention, I will now first refer to the accompanying drawings, embodying my improved apparatus or system for carrying out the process, in which drawings like characters designate the same parts in the several views, and in which—

Figure 1 is a diagrammatic view of my improved apparatus, or a systematic arrangement for carrying out my process, and

Fig. 2 is an enlarged sectional view, taken vertically and longitudinally through the treating tank, the flotation separator, and the mixing receptacle for the treating agent, the latter receptacle being shown disassembled with relation to the others, owing to the lack of space.

In the system illustrated, 1 designates a receiving and distributing tank for the oils to be treated; 2 an initial filter and washer;

3 a treating tank; 4 a supply receptacle for the treating agent; 5 a flotation separator and settling and collecting tank for the heavier precipitates; 6 a pressure filter, preferably of the well known type employing replaceable bag covered frames; 7 and 8 further filters and washers substantially like the filter 2, but employing different forms of filtering media; and 9 and 10 a pair of dry filters, coupled up as a unit, and having a storage chamber for the clear oil, to be drawn off at will in cans, barrels or otherwise for use.

Where desirable in practice, the various receptacles and filters are provided with heating coils, for promoting chemical action and increasing the fluidity of the heavy oils, illustrated at 11 only in the receptacles 3 and 4 of the sectional view Fig. 2; and similarly, the usual thermometers, water, and oil gages (not shown) are employed. Also faucets 12 may be used where desired for drawing off the oil contents from any of the filters or receptacles, and also cocks are generally illustrated at 13 for withdrawing sediment and for washing out purposes.

With the exception of the distributing tank 1, the treating tank 3, the receptacle 4, and the arrangement of the flotation separator 5, the remaining filter elements of the system are of well known constructions, and it is believed to be superfluous to further illustrate and describe them in detail, otherwise than to briefly say that the filter 2 is of that type in which the dirty oil is first filtered through waste or other medium; thence conducted to the bottom of a body of water; thence floated upwardly therethrough; thence again filtered; and finally passed to a chamber for the more or less clarified oil. The filters 7 and 8 are substantially the same as filter 2, excepting for the omission of the excess water overflow arrangement, the water in the oil at this stage of the operation being practically eliminated. Filters 9 and 10 are merely dry type filters, coupled up as a unit, and having a storage chamber for receiving the pure oil. The filtering medium for the filter 7 may be animal bone black; that of the filter 8 sponge and granulated cork; and that of the filters 9 and 10 linen terry and animal bone black, but it is obvious that other suitable filtering media might be interchangeably employed.

The receiving and distributing tank 1 may be divided into a plurality of compartments, illustrated at 14, 15 and 16, for collected oils of different degrees of clearness; and these compartments have man hole openings 17, serving as inlets, preferably provided with suitable screening means for initial straining.

18 designates a pipe line leading from the inlet of the filter 2 to the inlet of the filter 7, and 19 is a branch from the line 18 to the frame bag filter 6.

Short conduits 20 connect the compartments of the distributing tank 1 with the pipe line 18, suitable valves, generally designated by the numeral 21, being properly located and controlled to permit very clear oil, perhaps not necessary to chemically treat, to flow directly from the compartment 14, for instance, into the filter 6, or the filter 7, if desired, while the oil from either or both of the compartments 15 and 16 may at the same time flow in the opposite direction, through the branch connection 22, of the main line 18, into the filter 2, and through the whole system. Obviously also a branch pipe might be disposed between the main line pipe and the treating tank direct, for conveying the collected oil from any of the compartments direct to the treating tank, without passing through the first filter or washer.

23 is a pipe leading from the first filter 2 to the top of the treating tank 3, and 24 is a branch connection leading to the bottom of the tank. These have controlling valves 25 and 26, operated to permit the initially filtered and washed oil to flow into the treating tank 3 at its top or bottom.

27 is a pipe leading from the mixing receptacle 4, for the treating agent, to the bottom forward portion of the tank 3, and 28 is a branch connection leading to the top of the tank, suitable valves 29 and 30 being employed to guide the flow from the receptacle 4 to the bottom or top of the tank 3, as desired, and 31 designating a valve to control the amount of continuous discharge from the receptacle 4, proportioned to the condition of the oil in the treating tank 3.

The ends of the pipes 23 and 28 discharge into a man hole opening in the top of the tank, which may have a funnel entrance 32, screened or otherwise.

The treating tank 3 may have any suitable means for agitating the contents of the tank to cause a thorough impregnation or intimate commingling of the oil and water in the tank with the treating agent mixture from the receptacle 4. This agitating means is shown as comprising a rotatably mounted shaft 33, provided with radial blades or stirrers 34, driven in any suitable way, shown conventionally by the band pulley 35.

Also the receptacle 4 is provided with an agitator for thoroughly mixing the treating agent with clean, clear oil. This agitator 120 may consist of a rotatable shaft 36, shown conventionally as driven by the gearing 37, and having radially disposed supports 38 provided with depending blades or stirrers 39, coöperating with inwardly disposed baffles 40.

41 designates a pipe conduit leading from toward the top of the treating tank 3 to a funnel 42, capping the inlet elbow pipe 43, leading to the flotation separator 5.

The pipe 41 may have a controlling valve 44, and a branch pipe 45 leads from the pipe 41 to the tank 3, just above the bottom of the latter, the object of which is, that when its controlling valve 46 is open, the contents of the tank 3, above the sediment line may be drawn off into the flotation separator 5.

The flotation separator tank 5 is provided at its bottom with forwardly inclining baffles 47, which may be slightly spaced from the bottom of the tank to provide a clearance for precipitated impurities, between the baffle partitions, to be drawn off through the sediment cock 13.

48 designates a short upwardly disposed baffle plate, and 49 a longer downwardly disposed baffle plate, the latter forming with the former and with the end wall of the tank a passageway 50 or channel for the excess 20 water, conducting the latter to the water overflow 51, and thence through the waste water outlet 52 to a sewer or other discharge source.

A collecting trough or cup is provided to 25 receive the overflow of the floated oil, and the upper open top of this cup is preferably disposed slightly above the level of the water overflow 51. This collecting oil cup may be, as shown at 53, located inside of the 30 tank if preferred, and communicates, at its bottom, with an elbow outlet 54, and oil outlet pipe 55.

The oil outlet pipe 55, through its branch 35 56, communicates with the bottom of the pressure bag filter tank, but where the branch pipe 19 is employed in the system, the pipe 55 may be extended as shown to meet the pipe 19, in which case the branch 40 56 may be dispensed with if desired. Also this extension of the pipe 55 may be valved as shown, if desired.

From the top of the pressure filter 6 (of the replaceable frame bag covered type) a 45 pipe 57 leads to the inlet of the filter 7, through the line pipe 18, where the latter is employed, and this pipe 57 is provided with a controlling valve.

A pipe 59, having a controlling valve 60, leads from the top of the filter 7 to the inlet of the filter 8, and from the outlet of the filter 8 a discharge pipe 61, having controlling valves 64 and 65, leads to the unit type dry filters 9 and 10, and discharges therein through the drip nipples 62 and 63 and the 55 funnel openings 66, and after final dry filtration, the pure oil passes to a storage chamber within the filter casing, from whence it may be drawn off, as desired, through the faucets 12.

60 In carrying out the process, the collected oil is first strained into the compartments of the tank 1, according to its degree of cleanliness.

Any oil that is so clear that it is not essential to especially treat the same may be con-

ducted directly from its compartment, through the pipe line 18, to the filter 7, or by the branch pipe 19 to the filter 6, as desired, the proper valves 21 being opened and closed, respectively, to accomplish this end. 70 This will not interfere with the conduct of the oil from the remaining compartment or compartments through the whole system.

It will also be understood that it is not strictly necessary, although desirable, to 75 initially filter and wash the oil in the filter 2, and the number of filtrations, after the pressure filter 6, may be modified or enlarged as desired.

However, describing the process, step by 80 step as illustrated, the oil having been conducted to the filter 2 and passed therethrough, to initially remove many impurities and bad odors, is then delivered to the treating tank 3, where it is intimately commingled with the treating agent, through the agency of any suitable agitation means, illustrated in the drawings by the stirrer blades 34 in the treating tank, the treating agent having also been thoroughly mixed 85 with clean oil in the receptacle 4.

The oil laden mixture then passes into the flotation separator 5, which has been previously filled with water to the line of overflow, wherein it first descends until freed of 95 its clinging heavier impurities, which settle to the bottom of the tank, while the mixture floats upwardly through the water bath and over into the oil cup 53, and the excess water passes off at 51 to the waste pipe 52. 100

The mixture then passes through the oil outlet 54 to the pipe 55, which conveys it to the bottom of the pressure filter 6.

As has been previously stated, this filter 6, while it is believed to be unnecessary to 105 illustrate same in detail, may be of the well-known type, employing a series of gauze covered replaceable frames, which are in turn independently incased in cloth filter bags, the oil percolating through the filter 110 bag and gauze, by the pressure of its own weight, into the interior of the frames, from whence it is discharged, in a very thoroughly filtered condition, into a clear oil chamber, finally passing through the outlet 115 pipe 57, and successively through the remaining filters of the series, which final steps are obvious.

Up to the point of filtration through the bag frame filter 6, the treating material has 120 continued to act on the entrained oil to practically absorb colloidal substances therein, and to some little degree has bleached the oil. It now becomes necessary to separate the oil from its treating agent and the remaining insoluble suspended impurities.

Here again kieselguhr as the treating agent becomes extremely effective as a physical agency of separation, the innumerable walls of the microscopic cells providing 130

an enormous area of filtering surface, relative to the size of the mass, and the multi-form shapes and groupings of the cells, in overlapping and diverging relations, causing the penetrating fluid to filter therethrough in more or less diverted paths, so that the oil is substantially freed from all carbonaceous or other impurities, including the kieselguhr with its retained impurities, as it, the oil, passes through the bag filters to the interior of the filter frames, from whence it is discharged into a clear oil compartment.

During the operation of filtration in the bag frame filter, it is obvious that the flow of the treating agent will have been obstructed and halted, forming a layer or coating on the exterior surfaces of the filter bags of the frames, but the nature of kieselguhr is such that, instead of clogging up the pores of the filter cloths and retarding filtration, it acts reversely and very materially aids filtration, for it retains the gummy matters and remaining impurities, as the oil seeps through the sponge like porous mass as a substantially purified and clarified liquid.

While the oil is now in a substantially pure and clear state, it is obvious that perfection may be approached by further filtrations through the remaining filters of the system as illustrated.

It may also be stated that, where the oil from any of the compartments of the distributing tank 1 is led direct to the pressure filter 6, it may still be acted on by the treating agent, although in a less degree than if passed through the prior steps of treatment.

Having thus described my process and the improved apparatus for carrying out the same, what I claim is:

1. The process of reclaiming oils, which includes the steps of subjecting a conglomerate mixture, of impure oil and a proportionate amount of a suitable treating substance, highly buoyant and freely absorptive as to oil, to a bath of water in a flotation separator, for initially precipitating the heavier clinging impurities while floating the buoyant residue; and then causing said oil laden residue to flow from said flotation separator, as a washed conglomerate mass, into association with a permeable retarding agency, the flow of said treating substance and the substantial remaining colloidal and other suspended impurities being halted by said retarding agency while the oil freely percolates therethrough in a purified state, substantially as described.

2. The process of reclaiming oils, which includes the steps of introducing the impure oil into a treating tank with a proportionate amount of a suitable treating substance, highly buoyant and absorptive as to oil, then thoroughly agitating the contents

of said tank to provide a freely flowing conglomerate mixture; then flowing said mixture into a bath of water contained in a flotation separator, for initially precipitating the heavier clinging impurities while floating the buoyant residue; and then causing said oil laden residue to flow from said flotation separator, as a washed conglomerate mass, into association with a permeable retarding agency, the flow of said treating substance and the substantial remaining colloidal and other suspended impurities being halted by said retarding agency while the oil freely percolates therethrough in a purified state, substantially as described. 80

3. In a system for reclaiming oils, the combination of a treating tank for receiving the impure oil in conjunction with a proportionate amount of a suitable treating substance substantially as set forth; an outlet 85 for said tank; means for agitating the contents of said tank to provide a freely flowing conglomerate mixture of the impure oil and treating substance; a flotation separator tank in communication with the outlet 90 of said treating tank and itself having an oil mixture overflow, said separator tank being adapted to contain a substantial charge of water; and a filter tank in communication with the oil mixture overflow of said flotation separator tank and containing filtering means permitting of the percolation of oil therethrough while halting the flow of said treating substance and other impurities, the several elements coöperating and functioning substantially as described. 95

4. In a system for reclaiming oils, the combination of a filter tank for initially filtering the impure oil; a treating tank in communication with the oil outlet of said 105 filter tank for receiving the partially filtered oil and a proportionate amount of a suitable treating substance as set forth; an outlet for said treating tank; means for agitating the contents of said treating tank to 110 provide a freely flowing conglomerate mixture of the oil and treating substance; a flotation separator tank in communication with the outlet of said treating tank and itself having an oil mixture overflow, said 115 separator tank being adapted to contain a substantial charge of water; a pressure filter, of the type having replaceable bag covered frames, communicating with the oil mixture overflow of said separator tank and functioning as set forth; and final filtering means communicating with the interior of said bag covered frames, the several elements coöperating and functioning, substantially as described. 120

5. In a system for purifying oil, the combination of a treating tank for receiving the oil to be treated; a mixing receptacle, for a suitable treating agent, communicating with said treating tank; an agitator in said treat- 125 130

- ing tank for thoroughly commingling the contents thereof; a flotation separator communicating with said treating tank, and having an oil mixture overflow and an excess water overflow; and a filter tank in communication with the oil mixture overflow of said flotation separator, and containing filtering means permitting of the filtration of oil therethrough while halting the flow of said treating agent, substantially as described.
6. In a system for purifying oil, the combination of a treating tank; a receiving and distributing tank, for the oil to be treated, communicating with said treating tank; a supply receptacle, for a buoyant treating substance freely permeable as to oil, communicating with said treating tank; agitating means in said treating tank for intimately commingling the oil to be treated with said treating substance; a flotation separator communicating with said treating tank, having an oil mixture overflow and an excess water overflow; and a filter tank communicating with said oil mixture overflow, and containing filtering means permitting of the filtration of oil therethrough while halting the flow of said treating substance, substantially as described.
- 25 7. A system for purifying oil, including a receiving and distributing tank, having a plurality of compartments, a treating tank, and a pressure filter, all communicating in

the order named, and a by-pass conduit leading directly from said distributing tank to said pressure filter, suitable control cocks being disposed in the system, substantially as described.

8. A system for purifying oil, including a receiving and distributing tank, having a plurality of compartments, a treating tank, a pressure filter, and a final filtering means, all communicating in the order named, and a by-pass conduit leading directly from said distributing tank to said final filtering means, with a branch conduit leading from said by-pass conduit to said pressure filter, suitable control cocks being disposed in the system, substantially as described.

9. The process of reclaiming oils, which includes the steps of introducing the impure oil into a treating tank with a proportionate amount of a suitable treating substance, highly buoyant and absorptive as to oil; then thoroughly agitating the contents of said tank to provide a freely flowing conglomerate mixture; causing said mixture to flow into association with a permeable retarding agency, the flow of said treating substance and the colloidal and other suspended impurities being halted by said retarding agency while the oil percolates therethrough in a purified state, substantially as described.

In testimony whereof, I affix my signature. 65
OLIVER C. SWAN.
